UNITED STATES PATENT OFFICE.

CHARLES K. PEVEY, OF WORCESTER, MASSACHUSETTS.

ANNUNCIATOR AND FIRE TELEGRAPH.

SPECIFICATION forming part of Letters Patent No. 317,569, dated May 12, 1885.

Application filed July 23, 1883. (No model.)

To all whom it may concern:

Be it known that I, CHARLES K. PEVEY, of the city and county of Worcester, in the Commonwealth of Massachusetts, have invented a new and useful Improvement in Electric-Annunciator Alarms; and I do hereby declare that the following is a full, clear, and exact description of the invention, reference being had to the accompanying drawing, which forms a part 10 of this specification.

The object of my invention is to provide better and more desirable means whereby guests in hotels and boarding-houses can be aroused from sleep in case they wish to be called at 15 certain hours for departure, and in case of fire, and by which the person in charge at the office can give the alarm to one room or to all of the rooms in the house simultaneously without running from room to room, and can also be 20 made to answer the purpose of a call-bell from the sleeping-room to the office.

My invention consists of the arrangement of an alarm-bell and double or single acting swing-switch or a press-button switch in one 25 or more sleeping-rooms, connected by means of electric main battery and circuit-wires with a switch, and also with the annunciators now in use in the office or other room, so that when the switch in the sleeping-room is closed on 30 the bell and the switch in the office, being open, is moved to close the circuit it will set the bell ringing continuously in the sleeping-room until the person is aroused sufficiently to get up and switch it off, in doing which with the double- 35 acting switch it will announce the fact of his being up at the office through the annunciator without the use of the push-button switch, so that the push-button may or may not be used for this purpose, and can be used at any time 40 from the room to the office, if desirable.

By this device the customary unpleasant way 45 of rousing sleepers by rapping and calling at the door vocally, so annoying to the adjoining occupants, is avoided, besides it is often the case that a person when called in that manner will, half asleep and half awake, answer the call and drop immediately asleep again, and he is left to sleep it out, and find he has lost his train or failed to meet some important engagement; 50 but with my device the bell is kept ringing by the electric connections until the person gets

up and switches it off in his room, and he will not be likely to turn into bed again.

To enable others skilled in the art to put up and practice my invention, I will proceed to 55 describe its construction and operation.

Referring to the accompanying drawing, A denotes the office-room, and A' the sleeping-room.

B denotes the electric batteries, which may 60 be located in any convenient place.

E denotes a swing-switch in the office, and E" a double-acting swing-switch in the sleeping-room A', with bell F and a push-button switch, G.

Electric main battery-wire D extends through 65 all the rooms to complete a circuit. Wire C is a circuit-wire extending from the battery to screw P' under the lower end of swing-switch E to the right, and circuit-wire C connects to the 70 pivot-screw P of switch E, and extends to screw O under the lower end of switch E" to the right circuit-wire K, is fastened to pivot-screw O' of switch E", and extends to bell F. Circuit-wire J' extends from bell F to battery-wire D, 75 which completes this circuit with bell F and the batteries. Circuit-wire C is attached one end to battery-wire C and the other end to screw O" in switch E". Circuit-wire J" is attached one end to said screw O" and the other 80 end to the same screw that circuit-wire J is attached to under the push-button switch G, and thence to bell H', which has connection with the drop-tag magnet H by means of circuit-wire J⁴, thence to the main battery-wire D by 85 means of circuit-wire J³, which completes this branch of the circuit. The push-button switch G is operated by the circuit-wires C² and J through bell H' and the drop-tag A' to battery-wire D by wires J⁴ and J³, which completes 90 this branch of the circuit.

The arrows indicate the direction of the electric current, and n n the stop-pins of the switches, and the dotted lines the movement of the switches.

This device can in like manner be extended to any number of rooms.

To operate this invention switch E" in the sleeping-room should be set to the right, which closes the circuit on bell F at this point, as 95 shown, and switch E in the office set to the left, as shown, so that when moved to the right

it will close the circuit at this point through to bell F and set it ringing continuously until the sleeper is aroused sufficiently to get up and move switch E" to the left onto pin O", which shifts the circuit onto wires C" and J", and wire J under the push-button G, which extends to the bell H', and thence by wire J' to the drop-tag A' of the annunciator-magnet H, and thence by wire J", which completes this branch of the circuit with the main battery-wire D, and the batteries, thus announcing the fact that the person is up.

Switch E" should be left midway, as shown by the dotted lines, when not in use.

15 The push-button switch can be used for a call or notice from the room to the office at any time, if desired, without interfering with my device.

Having thus fully described my invention, what I claim, and desire to secure by Letters 20 Patent, is—

The combination, substantially as described, with the wires of a hotel-annunciator system, of an annunciator and circuit-closer in the office, and in each room a bell, push-button, and a switch in the bell-circuit, whereby the attendant in the office can operate an alarm in any room, and the occupant of the room can cause the bell to cease ringing and drop an annunciator-tag in the office. 25

CHARLES K. PEVEY.
